CLAIM

The ornamental design for a vehicle front fascia filler, as shown and described.

DESCRIPTION

FIG. 1 is a perspective view of a vehicle front fascia filler for mounting on the leftside of a vehicle (the rightside vehicle front fascia filler being a mirror image);

FIG. 2 is a front view thereof;

FIG. 3 is a side view thereof; and,

FIG. 4 is a top view thereof.

The broken lines in the drawings illustrate portions of the vehicle front fascia filler that form no part of the claimed design.
